UNITED STATES PATENT OFFICE.

HOWARD W. HARLEY AND JOSEPH BRENNER, OF PHILADELPHIA,
PENNSYLVANIA.

CIRCULAR-KNITTING MACHINE.

SPECIFICATION forming part of Letters Patent No. 364,345, dated June 7, 1887.

Application filed July 14, 1885. Serial No. 171,585. (No model.)

To all whom it may concern:

Be it known that we, HOWARD W. HARLEY and JOSEPH BRENNER, of the city and county of Philadelphia, and State of Pennsylvania, 5 have invented an Improvement in Knitting-Machines, of which the following is a specification.

Our invention has reference to stop-motions for knitting-machines; and it consists in certain improvements by which a brake may be automatically applied upon stopping the rotation of the needle-head; further, in so forming the brake that it may be applied or removed by hand, so as to allow the needle-head 15 to be turned by hand independent of the motor power, or while running, whereby the brake may be applied to the needle-head to slow down the motion, and in details of construction, all of which are fully set forth in 20 the following specification, and shown in the accompanying drawings, which form part thereof.

The object of our invention is to provide suitable brake mechanism to the needle-head, 25 whereby, when the same is thrown out of gear with the power-shaft, the brake may be automatically applied to stop spinning or rotation of the needle-head, due to the momentum imparted during the working rotation after being 30 disconnected from the power-shaft.

Our object is further to provide suitable means by which the said brake may be applied or removed by hand, so that when the needle-head has been stopped the brake may be removed without throwing the power mechanism 35 into action and the needle-head may be turned to find a broken thread, or while running, the brake may be applied without throwing off the power to reduce the speed of rotation of 40 the needle-head below that of its normal working velocity.

In the drawings, Figure 1 is a plan view of a knitting-machine with a stop-motion applied thereto embodying my improvements. Fig. 2 45 is a front elevation of the same, and Fig. 3 is a cross-section on line $x-x$ of Fig. 1.

P is the main frame of the machine.

A is the needle-head. B is the power-shaft. C is the power band-wheel, and D is the bevel- 50 pinion that meshes with the gear on the needle-head to rotate it. This bevel-pinion D is loose

upon the power-shaft B, and may be connected or disconnected by the clutch part E, which is operated by a lever, F, the movement of which in one or the other direction throws the clutch 55 into or out of action, so that the continually-rotating shaft B is connected with or disconnected with the pinion D, thereby positively rotating the needle-head A or allowing it to come to rest.

G is the brake-shoe, and is loosely connected at I with the short end of the lever H, fulcrumed at h on frame P, which lever is provided with a handle, J, by which it may be shifted to apply the brake G or to remove it 60 from the periphery of the needle-head A.

Hinged to the lever F, at M, is a bar, L, having a notch, L', upon its under side and near its free end, the said bar being passed through the slotted pivot-connection K, carried by the 70 lever H, the notch L' in said bar receiving a pin, k, in said part K, so that when the parts are in the position shown in Fig. 3 the rod L positively connects both the levers H and F, so that when one is moved the other is moved 75 also. Therefore when it is desired to stop the knitting-machine, the operator simply moves the lever F to withdraw the clutch part and free the pinion D, and the said action simultaneously moves the lever H, causing the 80 brake G to be automatically applied and thereby arrest the rotation or spinning of the needle-head. Upon throwing the clutch part into connection again the brake G is automatically removed.

The arrangement of the brake with the needle-head is such that the movement of the brake-shoe when being applied is in the direction of the rotation of the needle-head, and thereby requires very little exertion on the 85 part of the operator to stop the machine.

If it is desired to apply the brake while the machine is running, the bar L is raised so that the pin k is free of the notch L', and then the lever H may be operated by hand to apply 95 the brake G to retard the rotation of the needle-head; or, on the other hand, if we assume that the needle-head had been arrested by the automatic action of the lever H when withdrawing the clutch part E, then by raising the bar L the lever H may be moved to 100 remove the brake and allow the needle-head

to be rotated by hand to bring around any particular needle to the front of the machine.

From the foregoing it will be observed that the pivoted hand brake-lever has a short arm 5 to which the curved brake is connected, the curvature of which shoe corresponds to the curvature of the needle-head, the parts being so constructed that the throw of the small arm of the lever is substantially equal to the radial 10 movement of the shoe to or from the needle-head.

The means for rotating the needle-head and the clutch mechanism may be made in any of the well-known ways, the particular construction 15 not having any limitation on this improvement.

We do not limit ourselves to the particular 20 latching connection of the bar L and lever H, as it may be modified in various ways without departing from our invention, and the brake proper may be also modified or changed in construction so long as it accomplishes the object stated.

Having now described our invention, what 25 we claim as new, and desire to secure by Letters Patent, is—

1. In a knitting-machine, the combination, with the needle-head A, of the power shaft B, gearing D, to drive the needle-head, clutch E, 30 clutch-lever F, brake-shoe G, and pivoted lever H, carrying said brake shoe and having a fixed fulcrum, h, and independent of the clutch-lever, whereby the needle-head may be slowed down by application of the brake without in-

terfering with the power, and the power may 35 be thrown off and the brake applied.

2. In a knitting-machine, the needle-head, in combination with the power-shaft, the gearing connecting said power-shaft with said needle-head, clutch mechanism to put said 40 gearing into or out of action with said power-shaft, a lever to operate said clutch mechanism, a brake acting upon said needle-head to arrest its rotation, connecting mechanism, substantially as set forth, between the clutch-lever 45 and the brake, whereby the latter is automatically operated upon moving the clutch, and the latching devices by which the clutch-lever and brake mechanism may be connected or disconnected, to the end that when desired the 50 brake may be operated by hand independently of the action of the clutch, substantially as and for the purpose specified.

3. The combination of the needle-head A, gearing D, clutch part E, power-shaft B, clutch-lever F, brake-shoe G, brake-lever H, having the slotted piece K, provided with pin k, and bar L, hinged to the lever F and having notch L', adapted to catch over the pin k, substantially as and for the purpose specified. 55

In testimony of which invention we hereby set our hands.

HOWARD W. HARLEY.
JOSEPH BRENNER.
